Geo. Kirk

Attorney

UNITED STATES PATENT OFFICE

DAVID C. SMITH, OF TOLEDO, OHIO, ASSIGNOR TO KADOW FOUNDATION INC., OF TOLEDO,
OHIO, A CORPORATION OF DELAWARE

VISIBILITY PROMOTION

Application filed February 4, 1929. Serial No. 337,490.

This invention relates to visibility promoting devices.

This invention has utility when incorporated in rounded cone elements.

Referring to the drawings:

Fig. 1 is a view of an embodiment of the invention in a sign, parts being broken away;

Fig. 2 is a detail view on an enlarged scale of one of the elements as assembled to promote visibility in the sign of Fig. 1;

Fig. 3 is a section on the line III—III, Fig. 2;

Fig. 4 is a view of further visibility promotion uses of the elements and instead of being in a sign as in Fig. 1, being about a headlight and in the radiator cap, the former to supplement visibility between approaching cars, and the latter to increase visibility range of car driver, more particularly as under traffic lights;

Fig. 5 is a detail view of the element; and

Fig. 6 is a section on the line VI—VI, Fig. 5, looking in the direction of the arrow.

General support or frame 1 is shown as having letter outline members 2 providing mounting seats in which are mounted rounded cone elements 3 retained in assembly position by nuts 4. Conveniently in practice, sockets 5, of a type say for mounting incandescent light bulbs, may carry plugs 6 having terminal threaded portions 7 to be engaged by the nut 4. This plug 6 is additionally provided with concave seat 8 so that as nut 4 is brought into position, its overhang 9 may contact with taper portion 10 of the element 3 in the region of cylindrical portion 11 remote from rounded top or outer terminus 12 of this element 3. This element 3 on the side of the cylindrical portion 11 remote from the rounded cone portion has convex portion 13 coacting with the seat 8.

In practice, this convex portion 13 is provided with opaque coating 14. In some instances this is merely an opaque background preferably of a luster for promoting reflection, and such reflection may be even of a mirror or silvering character.

However, in practice, with this element 3 of transparent material as glass, the coating for the convex portion of the base may be in

contrasting colors, lustrous for promoting reflection, say of an enamel, colored varnish, or Duco character. This parti-colored scheme may be with region 15, yellow; region 16, green; region 17, purple.

55

These parti-colored elements while of attention-drawing attractiveness for signs or other visibility promoting devices, may have, instead of a contrasting color, a traffic or caution signal color as amber, red, or green, when the elements 3 are assembled in ring 18 of motor vehicle headlight for motor vehicle 19. In this assembly, the elements in one headlight may be red and in the other green, or each may be either of these colors or amber according to the fancy of the driver or in conformity with traffic regulations.

60

For the convenience of the driver of the vehicle 19, radiator cap 20 may have element 3 therein. This element 3 with its reflector 70 coating 14 on its base and the element 3 of glass, serves as a vision range promoting device for the driver of the vehicle, especially of value where luminous stop signals or traffic regulation devices are installed.

75

With the closed car type of motor vehicle and the vision of the driver upward restricted, this radiator cap carried element 3 disclosed to the driver the flash change of red to amber or green, or vice versa, so that from 80 the normal driving view position, the operator may check on the condition of the signal for being taken into account in his driving of the vehicle.

This assembly may be used in some practices in lieu of or to displace electric incandescent light bulbs.

85

What is claimed and it is desired to secure by Letters Patent is:

1. A double convex visibility promoting device comprising a rounded cone reflection element, a plug support element embracing fitting therefor providing a seat, and a complementary fitting with which said support fitting may be detachably engaged for mounting the element.

90

2. A visibility promoting device comprising a rounded cone reflection element having a flare base portion, a plug support having a seat for the base, and a plug engaging nut 11.

95

for engaging the base, said nut having an overhang for detachably assembling the element with the plug in thereby anchoring the element in seat-engaging position with the 5 plug.

3. A visibility promoting device comprising a rounded cone reflection element having a flare base portion, and an externally threaded plug support having a seat therein 10 for the base, said seat having means overhanging the flare portion in thereby anchoring the element with the support.

In witness whereof I affix my signature.

DAVID C. SMITH.
